STOP MOTION FOR CARDING MACHINES

Benjamin F. Underwood and John C. Grant,
Easley, S. C.

Application June 16, 1945, Serial No. 599,784

1 Claim. (Cl. 19—167)

This invention relates to a stop motion for carding engines or carding machines as used in the preparation of fibers. Carding engines have a carding cylinder, flats, a licker-in roll, a doffer roll, a stripper, a feed roll and a trumpet and coiling mechanism whereby the carded fibers as they are taken from the carding machine are stripped from the doffer roll and passed through a trumpet and a suitable coiling mechanism to deposit the sliver or roving into a suitable can for further processing.

Great inconvenience and damage has heretofore been caused to carding machines by foreign objects such as pieces of metal, wood and the like being imbedded or contained in the lap of fibers being passed into the carding machine which causes great damage to the mote knives, licker-in, flats, and sometimes damaging the clothing on the carding cylinders, which is very expensive. Also much time is lost in repairing the same.

It is an object of this invention to provide a stop motion mechanism for stopping the feed roll and the doffer roll of a carding machine when a foreign object is disposed within the lap of fibers being carded or when the lap of fibers is too thick as where an incoming lap end is lapped over an outgoing lap end to make the fibers too thick at that point which will clog the carding machine. This invention will stop the doffer and the feed roll and prevent the card from choking down which otherwise would result where the overlapped ends of two adjacent webs of fibers were passed into the machine.

It is another object of this invention to provide means automatically operable for moving the doffer lever to stop the feed roll and the doffer roll when the lap becomes too thick or when foreign objects such as pieces of metal and the like are disposed within the lap being fed into the carding machine.

It is another object of this invention to provide means adapted to be associated with the feed roll of a carding engine and having a connection for manipulating the doffer lever of the carding engine to quickly stop the feed roll and the doffer roll when a foreign object such as a piece of metal and like is disposed within the lap being processed by the carding machine or when the lap is too thick at any point or thick enough to result in choking of the carding machine.

Some of the objects of this invention having been stated, other objects will appear as the description proceeds when taken in connection with the accompanying drawings in which:

Figure 1 is a side elevation of a carding machine and showing the invention attached thereto;

Figure 2 is a top plan view of Figure 1;

Figure 3 is an elevation of the other side of the 5 left hand end of the carding machine from that shown in Figure 1 or an elevation being taken substantially along the line 3—3 in Figure 2;

Figure 4 is a vertical sectional view taken substantially along the line 4—4 in Figure 2;

Figure 5 is an end elevation of the right hand end of Figure 1 looking from substantially along the line 5—5 in Figure 1;

Figure 6 is an elevational end view looking at the left hand end of Figure 1, and omitting the 15 feed roll and brackets for holding the lap roll.

Referring more specifically to the drawings, the 20 numeral 10 indicates the uprights of the frame of a carding machine having horizontal base bars 11 and top longitudinally extending frame bars 12. This carding machine has a conventional rotary cylinder 13 having suitable card clothing thereon. The machine has a set of flats 14 which is schematically shown and has a doffer roll 15 provided with a shield 16 over its drive wheels 25 16a. It also has a suitable bracket 17 on each side having in each bracket a slot 18 in which the lap pin 19 of a lap roll 20 is adapted to be disposed. The lap 21 extending from the lap roll 20 is fed into the machine by means such as a feed 25 roll 22. Mounted on the top longitudinal bars 12 are the bearings 23 having vertical slots 23a in which the ends of feed shaft have vertical movement. The feed roll 22 is pressed against the lap 21 by means of the horizontal top frame 30 bars 12 having rising suitable uprights 24 in which one end of levers 25 are loosely mounted, each of these levers having a bearing surface 26 and on the outer ends of these levers 25 are mounted weights 27 which are adjustable along the levers 35 40 25 for regulating the amount of pressure applied to the lap 21. The feed roll 22 is driven by any suitable means such as a pinion 28 having a geared connection with pinion 29 which is driven by pinion 26 connected to the driven mechanism 45 of the machine not shown. The above described mechanism is conventional and it is with this conventional mechanism that the invention is adapted to operate.

Rotatably mounted in the upper portion of the 50 end uprights 10 is a shaft 30 which is coupled together by a coupling 31 and on one end of this shaft is mounted an arm 32 which has connected thereto a U-shaped rod 43 which has one arm mounted in a suitable hole in the free end of 55 the arm 32 and the other arm projecting into a

suitable hole in the weight 27. On the other end of shaft 30 is secured an arm 33 which likewise has one leg of another U-shaped member 34 piercing the free end thereof, while the upper end of this U-shaped member 34 penetrates a suitable hole in the other weight 27 on the other lever 25.

Also adjustably secured on the shaft 30 is an arm 35 which projects downwardly and has pivotally connected thereto one end of a rod 36, 10 which rod has a suitable coupling 37 therein intermediate its ends for overall adjustment of the length of the rod. The other end of the rod 36 is pivotally secured as at 38 to the upper end of a tripping lever 39 pivoted on a pin 40 which 15 is disposed in the lower end of brackets 41 and 41a whose upper ends are secured to one of the guards 16.

Mounted between the brackets 41 and 41a is a doffer lever trigger 44 which is also mounted on the pin 40. This doffer lever trigger 44 is substantially an inverted L-shape and on the upper surface of its upper leg is adapted to rest a conventional doffer lever 45 of the carding machine. This doffer lever controls the feed roll 22 to stop the same when the doffer lever is actuated. The lower end of the tripping arm support 39 has an outwardly and downwardly and then outwardly projecting pin 46 which projects adjacent to the lower and inner side surface of the doffing lever trigger 44.

The lap 21 is supported in any suitable manner. It may slide along a suitable metal plate or may be conveyed by a suitable endless conveyor 50 suitably supported by a plate 51 which, of course, is conventional in a carding machine.

It is thus seen that when a portion of the lap which is too thick and which would clog the carding machine, or a foreign object, such as a piece of metal or other object, passes under the feed roll 22, one or both of the levers 25 will be raised upwardly which will raise one or more of the weights 27 which will move arms 32 and 33 and will oscillate shaft 30 which will swing lever 35 to the left of Figure 1 which will swing the trigger arm support 39 in a counterclockwise manner which will raise the doffer lever trigger 44 oscillated on pin 40 in a counterclockwise direction which will raise the free end of doffer lever 45 to stop rotation of the feed roll and 50 doffer roll.

This will occur whether the thick place or the foreign object in the lap occurs in the center of the feed roll 22 or out near one edge of the same and that is why there is provided the shaft 30 extending all the way through the machine and also an arm suitably connected, as described, to each of the weights 27.

In the drawings and specification there has been set forth a preferred embodiment of the invention, and although specific terms are employed, they are used in a generic and descriptive sense only, and not for purposes of limitation, the scope of the invention being defined in the claim.

We claim:

In a carding machine through which a lap of fibers is adapted to be passed, said machine having a feed roll for feeding the lap of fibers into the machine, and also having a doffer roll, said 20 machine also having weighted levers for pressing the feed roll into engagement with the lap of fibers, said machine also having a doffer lever for controlling rotation of the feed roll and the doffer roll, a bracket mounted on the machine and having a horizontal pivot pin, a tripping lever pivoted intermediate its ends on said pin, a doffer lever trigger pivoted on said pin and having a cam face on its upper end on which the free end of the doffer lever rests, said tripping lever having a laterally projecting pin in its 25 lower end fitting against the lower end of the doffer lever trigger, a rod pivotally connected to the upper end of the tripping lever and extending longitudinally of the machine, a shaft oscillatably mounted in the machine and extending across the machine below the weighted levers, an arm fixedly secured on each end of the shaft, the free ends of said arms having a link pivotally secured thereto and the other ends of the links being secured to the weighted levers, a downwardly projecting arm secured on the end of the shaft on the same side of the machine where the tripping arm support is mounted and having its lower end pivotally connected to the other end 35 of said rod, whereby when one of the weighted levers is raised the shaft will be oscillated to swing the tripping lever on its pin to pivot the doffer lever trigger to thus move the doffer lever to stop rotation of the feed roll and the doffer roll.

BENJAMIN F. UNDERWOOD.
JOHN C. GRANT.
